DESIGN FOR A COMBINED GOLF COURSE SIGN AND RACK

William G. Dunn, Clarinda, Iowa

Application July 15, 1940, Serial No. 93,632

Term of patent 14 years

To all whom it may concern:

Be it known that I, William G. Dunn, a citizen of the United States and a resident of Clarinda, in the county of Page and State of Iowa, have invented a new, original, and ornamental Design for a Combined Golf Course Sign and Rack, of which the following is a specification, reference being had to the accompanying drawing forming part thereof.

The figure is a perspective view of a combined golf course sign and rack showing my new design.

I claim:

The ornamental design for a combined golf course sign and rack, substantially as shown.

WILLIAM G. DUNN.
